ROBERT J. HEARNE, OF NEW YORK, N. Y.

POWER-TABLE FOR FACTORY USE.

1,163,340.

Specification of Letters Patent.

Patented Dec. 7, 1915.

Application filed May 29, 1915. Serial No. 31,123.

To all whom it may concern:

Be it known that I, ROBERT J. HEARNE, a citizen of the United States, and a resident of New York city, in the county of 5 New York and State of New York, have invented certain new and useful Improvements in Power-Tables for Factory Use, of which the following is a specification.

The invention pertains more particularly 10 to tables or benches to be used in factories for supporting high speed sewing machines and other small machines, with the proper driving connections therefor, and the purpose of the invention is to provide a table 15 or bench of this character composed of transverse or cross-sectional units properly spaced apart at their outer portions and capable, except possibly at the end units, of supporting a machine at each end thereof. 20 My invention has been produced with the view of providing a very durable bench or table of the character referred to adapted more particularly for high speed sewing machines of the kind used in the manufacture 25 and trimming of hats, although of course the bench or table may be used for supporting small machines other than sewing machines.

Power benches or tables for sewing machines, particularly hat sewing machines, as heretofore produced, have been deficient in 30 many ways; they have been lacking in the requisite degree of strength and rigidity and consequently have been inefficient in firmly 35 supporting the sewing machines, as a consequence of which the machines have created a great deal more noise than otherwise would be necessary. The lack of strength and rigidity in the benches or tables has also 40 resulted in the table requiring to be renewed or repaired with undue frequency and in the development of other undesirable conditions. Many of these tables as heretofore made have consisted of three long parallel 45 sections weakened by cutting at the points where the operators are supposed to sit and fastened together in such manner that the construction was rickety and the table or bench vibrated badly during the operation 50 of the high speed machines. In addition, these prior tables could only be moved by taking them entirely apart so that on moving one of the prior tables from one place to the other the material moved was mainly 55 a pile of lumber.

My invention provides a particularly durable structure and one in which each cross-sectional unit is self-contained and can be moved as a whole. The table or bench as a whole supports a driving shaft extending 60 from end to end thereof and this shaft must of course be detached before the cross-sectional units may be separated for removal. A table of any desired length may be built up of the sectional units, and if at any time 65 a longer table or one of increased capacity should become necessary, an additional unit or additional units may be added to the table.

I illustrate my invention herein as embodied in a bench or table for supporting hat sewing machines, with the driving connections therefor, Figure 1 being a top view, 70 of a bench or table embodying my invention; Fig. 2 a side elevation of the same, 75 Fig. 3 a vertical transverse section on a larger scale, taken on the dotted line 3—3 of Fig. 1, Fig. 4 a vertical longitudinal section, partly broken away, through the table taken on the dotted line 4—4 of Fig. 1; Fig. 80 5 a detached view, partly broken away, of one of the table units plus one of the longitudinal members connecting said units and suitably spacing them apart; Fig. 6 a horizontal section through the four legs of one 85 unit of the table with the means connecting and bracing them so that the unit as a whole may be moved about with convenience, the section being on the dotted line 6—6 of Fig. 3, and Fig. 7 an enlarged detached view, 90 partly broken away and partly in section, of one of the table legs and connections therefor, the sectional portion of Fig. 7 being taken on the dotted line 7—7 of Fig. 6.

In the drawings, 10 designates the two 95 end units, as a whole, of the table or bench, 11 each of the intermediate units as a whole, and 12 longitudinal members connecting said units in pairs and affording auxiliary 100 tables upon which the operatives may place small articles and which afford supports for drawers within which the operatives may keep small items incidental to their work. There will be employed as many units 11 as 105 may be required and these units will be connected together and suitably spaced apart by the members 12. The outer units 11 will also be connected with the end units 10 by the members 12.

Each unit 11 comprises a strong durable 110

top or bed 13 preferably of laminated character, four legs 14, one being at each corner of the said top or bed and preferably being of pipe construction, a center cast leg or support 15 whose outline is shown more clearly in Fig. 3, a brace 16 extending upwardly and outwardly from about the middle portion of the leg or support 15 and secured at its upper outer end by means of a bolt 17 (Fig. 4) and suitable transverse and longitudinal rods 18, 19, respectively, connecting the four legs 14, said rods being bolted to clamps 20 affording tubular or sleeve portions 21 of split ring character embracing 15 and tightening upon said legs, as shown more particularly in Figs. 6 and 7.

The top 13 of each unit is of considerable thickness and of laminated character as aforesaid and all this is for the purpose of providing a top which will be lasting, very durable, capable of withstanding the strains to which these power benches are subjected and not liable to warp, which is a great objection to benches supporting high speed sewing machines, and the top or bed 13 to each unit 11 is greater in width than length and extends laterally beyond the connecting members 12 for the units 11. Upon diagonally opposite corners of each top or bed 13, this being the left hand corner facing the side edge of said top or bed, are mounted sewing machines 22, whose work supporting portions extend over the end edge of said top or bed, as indicated in Figs. 1 and 2, to allow a hat for instance to revolve on a plane lower than the sewing machine and outwardly from the transverse edge of the table or bed 13, as the work proceeds in the ordinary course of sewing hats made of braid, straw and the like. In trimming hats already formed the same condition exists, that of the hat extending downwardly from the bed plate of the sewing machine and along the transverse edge of the top or bed 13. The top or bed 13 of each unit 11 is, adjacent to the drive wheel of the sewing machines, vertically slotted, as at 23, to permit the usual driving belt 24 to extend therethrough and be connected with the drive wheel of the sewing machine. The belt 24 is mounted at its lower portion on a friction transmitter 25 of usual character suspended below the top or bed 13 and controllable from the foot of the operative by means of the customary foot treadle 26 and connecting rod 27, as usual. The constantly rotating member of the friction transmitter mechanism is driven by a belt 28 from the power shaft 29 and belt wheel 30 thereon. The power shaft 29 extends the full length of the entire bench or table and the mechanism for driving a sewing machine therefrom as just hereinbefore referred to and as illustrated in the various figures of the drawing, is duplicated for each machine on the units 10,

11, this mechanism being of known character and therefore requiring no special description.

The legs 14 are preferably each in one integral piece of piping and have flanged feet 31 secured upon their lower ends and sockets 32 secured upon their upper ends and which sockets are formed with laterally extending arms 33 which are fastened to the top or bed 13, as shown in Fig. 3; the screws for securing the arms 33 at those corners of the top or bed 13 not directly supporting a sewing machine, will be of the usual character indicated by dotted lines 34, and in addition to the screws which secure the arms 33 to the lower side of the top or bed 13 at those corners thereof directly supporting sewing machines there are also others in the form of bolts 35 which extend downwardly from the sewing machines through holes 36 in the top or bed 13 and through holes in the arms 33 and receive on their lower ends thumb nuts 36 by which in connection with the bolts 35 the sewing machines may be detachably held in position on the table top or bed and the arms 33 clamped against the lower surface of said top or bed, as shown at the upper left hand corner of Fig. 3.

It is to be observed that the legs 14 are at the extreme corners of each table top or bed 13 and so disposed therefore as to properly and with requisite rigidity support said top or bed and the sewing machines thereon, strength and prevention of vibration being thereby secured. Each unit 11 is further strengthened as to its supporting members and as a whole by means of the transverse and longitudinal bars 18, 19, these rods being horizontal and located on a plane suitably above the power shaft 29 and rigidly secured by the clamps or coupling members 20. The clamps or coupling members 20 each have a split-sleeve portion 21 whose ends are formed with apertured lugs or ears 37 and each of said portions 21 is formed with a rigid ear or lug 38. Each rod 18 extends through the ear 38 of one clamp or coupling member 20 and through both ears or lugs 37 of the next aligned clamp or coupling member 20, as shown at the upper and lower portions of Fig. 6, and the rod 18 at one end has a nut 39 to engage the lug 38 and at its other end is also threaded and has a nut 40 by which, against the resistance of a washer 41 on the rod, the lugs 37 may be forced toward each other and the sleeve member 21 of the coupling thereby clamped firmly against the leg 14. The longitudinal rods 19 correspond in construction, arrangement and function with the rods 18, each of said rods 19 having a nut 42 to engage a lug 38 of one coupling member 20 and also a threaded end and nut 43 at its other end, whereby the ears 37 of the coupling member at said end of the rod 19 may,

against the resistance offered by a washer 44, be forced toward each other so as to firmly clamp the coupling member on the leg 14 and at the same time rigidly secure the rod itself. The tightening of the nuts 40, 43 serve to firmly and rigidly secure the rods 18, 19 in proper relation to each other and to rigidly connect the legs 14.

The central supporting frames or legs 13, 15 will be castings, as clearly shown, and extend laterally and centrally below each top or bed 13 and said supporting frames or legs 15 are each formed with two feet 45 to engage the floor 46 and at its upper end 15 with a laterally extended flange or surface 47 upon which the top or bed 13 is rigidly secured by screws 48. The supporting frames or legs 15 are each formed with a cross-bar 49 and upon these cross-bars are secured by bolts 50 customary hangers 51 for the bearings for the driving shaft 29. The hangers 51 are in themselves of customary form and construction and hence the details thereof need not be gone into. The driving shaft is supported by all of the frames or legs 15, since said shaft extends the full length of the table or bench. Upon the cross-bars 49 of the supporting frames or legs 15 I secure by bolts curved brackets 30 or arms 52 extending downwardly and toward each side of the table or bench, as shown in Fig. 3, and to the outer ends of these arms 52 I secure by bolts long downwardly and inwardly inclined boards 53 which serve as skirt guards for the operatives while at work, these boards 53 keeping the skirts of the operatives from being caught on the power shaft 29 or wheels 30 or between the said wheels and belts 28. The skirt guards or boards 53 are safety devices and their use is therefore optional, although highly desirable.

The brace 16 for each unit 11 is secured at its upper end by the bolt 17 as aforesaid, said bolt being extended through a laterally turned ear at the upper end of said brace, as shown in Fig. 4, and fastened by a nut. The braces 16 each incline inwardly and downwardly from the bolts 17; at their lower ends each brace is formed with an angular flange 54 which engages the side of the cross bar 49 of the supporting frame or leg 15 and receives the head of the bolt 50 by which the hanger 51 is secured to said cross-bar 49. The upper end of each supporting frame or leg 15 is not only fastened to the top or bed 13 of each unit by screws 48, but also by a bolt 55 which passes downwardly through a hole in the center of said table or bed and through a hole in the upper transverse member of the frame or leg 15 and receives a nut 56 as shown in Figs. 3 and 4, whereby the frame or leg 15 becomes rigidly secured by very durable means in proper relation to the top or bed

13, and said top or bed 13 becomes very firmly held down upon said frame or leg 15.

Each unit 11 is, as may be understood from the description already presented, complete and self-contained and may be applied to or removed from the bench or table as an entirety, all the parts being thoroughly fastened together and the whole being rigid and of very durable character. In taking the table apart so as to move it, it will of course be necessary to remove the driving shaft 29 and skirt guards 53, since the driving shaft and skirt guards extend through all of the units.

The end units 10 while of the same extent laterally as the units 11, are less in longitudinal width and each of said units is intended to support one sewing machine. Each of the units 10 is equipped with legs 14 connecting rods 18, 19, coupling clamps 20, feet 31 and upper end sockets 32 having arms 33 to receive and be secured to the top or bed 57 corresponding exactly with the like legs and other parts of the units 11, and therefore the description of these parts as applied to the units 11 need not be repeated as to the units 10. I number the tops or beds of the units 10 with the number 57, because they differ somewhat from the tops or beds 13 of the units 11. The top or bed 57 of each unit 10 is formed with a slot 58 for the belt of a sewing machine, this slot being at one side of one top or bed 57 and at the opposite side of the other top or bed 57, as shown in Fig. 1.

Below the outer edge of the top or bed 57 of each unit 10 is a supporting leg or frame 59 corresponding with the supporting frames or legs 15 of the units 11 and therefore not requiring special description. The upper ends of the supporting frames or legs 59 are secured to the tops or beds 57 by means of screws 60 and a bolt 61 corresponding with the screws 48 and bolt 55 indicated in Fig. 3 as securing the supporting leg or frame 15 to the top or bed 13 of a unit 11. A downwardly and outwardly inclined brace 62 aids in securing the top or bed 57 of each unit 10 from the supporting frame or leg 59, and this brace 62 corresponds exactly with the brace 16 used in the units 11 with the exception that it inclines downwardly and outwardly instead of downwardly and inwardly, this difference in inclination being rendered necessary from the fact that the units 10 are end units. The lower ends of the braces 62 are bolted to the supporting legs or frames 59 and the upper ends of said braces 62 are secured by bolts 63 corresponding with the bolts 17 of the units 11.

The units 10, 11 are arranged in longitudinal series and are connected together and suitably spaced apart by the central longitudinal members 12, these members all being substantially alike and each being a piece

of board having at its upper side edge-flanges or cleats 64 which extend only between the tops or beds of the units and at its lower side drawers 65 for the use of the 5 operatives. The cleats 64 form between them shallow receptacles upon which the operatives may place such small articles or work as may be found convenient.

The members 12 between each pair of 10 units 11 create a space between said units and extend about up to the upper flanged ends of the supporting frames or legs 15, as shown at the middle portion of Fig. 1, and said members 12 are secured to the tops or 15 beds 13 of the units they connect by means of screws 66 and bolts 17, 67, the bolts 17 being the ones hereinbefore referred to as securing the upper ends of the braces 16 and the bolts 67 being independent bolts extending downwardly through the top or bed and underlying portion of the members 12. The 20 members 12 connecting the end units 10 with the adjacent units 11 correspond with the members 12 connecting the units 11 in pairs, 25 as may be observed from the end portions of Figs. 1 and 2, and these end members 12 are secured at one end below the top or bed 57 of the end units by means of screws 68 and the bolts 63 by which the upper ends of the 30 braces 62 are secured to said tops or beds, the screws 68 corresponding exactly with the screws 66 employed in fastening the intermediate members 12 to the units 11. The other or inner end of the end members 12 35 are fastened to the underside of the tops or beds of the adjacent units 11 by means of screws 69 and bolts 17, 71 respectively, the bolt 71 being an independent bolt, as shown in Fig. 1, and serving for the inner end of 40 one end member 12 while the bolt 17 serving for the inner end of the other end member 12 is the bolt which secures the upper end of the brace 16 to the top or bed of the unit 11.

I only illustrate two of the intermediate 45 units 11, but it will be readily understood that this power table or bench is a built-up structure so far as length is concerned and that as many of the units 11, with the appropriate connecting and spacing members 12, 50 will be made use of as may be necessary. Ordinarily a larger number than two of the intermediate units 11 will be employed, but the illustration in Figs. 1 and 2 represents the invention so long as it is understood that 55 the invention is not confined to the employment of any special number of units of the character described.

The connecting and spacing members 12 are less in width than the tops or beds of the 60 units, and hence between the side portions of the units are left gaps or spaces, which I will number for purposes of identification 72, for the convenience of the operatives seated at the machines 22. The gaps or 65 spaces 72 are essential so that the operative

may sit at the proper relation to the machine 22 and to the work being treated by said machine, and it is to be observed that each operative sitting at a sewing machine may not only conveniently employ the gap 70 or space 72 for a portion of her body, but may also make use of the adjacent portion of the top or bed of the unit next adjacent to her for placing the work or material thereon, this convenience arising from the 75 fact that the sewing machines so far as the units 11 are concerned, are at the left hand corner of each side of the unit, as hereinbefore explained. The operative sitting at a sewing machine may, therefore, not only have the convenience of the corner portion 80 of the unit on which the machine is placed, but also the corner portion of the adjacent end of the adjacent unit, as well as the exposed top of the adjacent connecting and 85 spacing member 12 and the drawer supported by said member.

What I claim as my invention and desire to secure by Letters Patent, is:

1. A factory work bench or table comprising a plurality of units and members connecting the same, said units comprising table or bed portions, supporting legs at the corners thereof, a transverse supporting leg frame for and secured to each bed portion 90 and rods connecting said corner legs, and said connecting members affording auxiliary tables and being less in width than the table portions of said units and secured at their ends thereto and spacing the same apart. 100

2. A factory work bench or table comprising a plurality of units and members, connecting the same, said units comprising table or bed portions, supporting legs at the corners thereof, a transverse supporting leg 105 frame for and secured to each bed portion and rods connecting said corner legs, and said connecting members affording auxiliary tables and being less in width than the table portions of said units and secured at their ends thereto and spacing the same apart, 110 and said connecting members having cleats at their opposite upper edges and sliding drawers at their lower sides.

3. A factory work bench or table comprising a plurality of units and members connecting the same, said units comprising table or bed portions, supporting legs at the corners thereof and a transverse supporting leg frame for and secured to each bed portion, and said connecting members affording auxiliary tables and being less in width than the table portions of said units and secured at their ends against the lower surface thereof and spacing the same apart, said units each having an inclined brace secured at its lower end to said transverse frame and at its upper end to an underlapping portion of one of said connecting members and the table or bed portion of the unit. 120 125 130

4. A factory work bench or table comprising a plurality of units and members connecting the same, said units comprising table or bed portions, supporting legs at the corners thereof, rods connecting said corner legs and means for tightening said rods in their connection with said legs, and said connecting members affording auxiliary tables and being less in width than the table portions of said units and detachably secured at their ends thereto and spacing the same apart. 5
5. A factory work bench or table comprising a plurality of units and members connecting the same, said units comprising table or bed portions, supporting legs at the corners thereof and means engaging and connecting said legs comprising clamps encompassing and bound to said legs and rods connecting said clamps, and said connecting members affording auxiliary tables and being less in width than the table portions of said units and detachably secured at their ends thereto and spacing the same apart. 10
6. A factory work-bench or table comprising a plurality of units and members connecting the same, said units comprising table or bed portions, supporting legs at the corners thereof and means engaging and connecting said legs comprising clamps encompassing and bound to said legs and rods connecting said clamps, and said connecting members affording auxiliary tables and being less in width than the table portions of said units and detachably secured at their ends thereto and spacing the same apart. 15
7. A factory work bench or table comprising a plurality of units and members connecting the same, said units each comprising table or bed portions, supporting legs at the corners thereof, a transverse supporting leg frame for each bed portion, means for securing the ends of the upper portion of said frame to the lower side of said table or bed portion and a bolt extending downwardly through said bed portion and the upper part of said frame and securing said 20
- frame and said bed portion together, and said connecting members being of table formation and less in width than the table portions of said units and extending closely below the same and spacing said portions apart, said units each having an inclined brace secured at its lower end to its said transverse frame and at its upper end being below an underlapping portion of one of said connecting members, and a bolt extending through the bed portion of the unit, said underlapping portion of the connecting member and the upper end of said brace. 25
8. A factory work bench or table comprising a plurality of units and members connecting the same, said units each comprising a table or bed portion, supporting legs at the corners thereof and a transverse supporting leg frame for and secured to each bed portion and having hangers for a power shaft, and said connecting members affording auxiliary tables and being less in width than the table portion of said units and secured at their ends against the lower surface thereof and spacing the same apart, said units each having an inclined brace secured at its lower end to said transverse frame and at its upper end to the table portion of the unit adjacent to its outer transverse edge and each unit being equipped with power transmission devices and slotted for the passage therethrough of the driving belt of a machine. 30
9. A factory work bench or table comprising a plurality of units and members connecting the same, said units each comprising table or bed portions, supporting legs at the corners thereof, a transverse supporting leg frame for and secured to each bed portion and a stiffening member, and said connecting members affording auxiliary tables and being less in width than the table portions of said units and secured at their ends thereto and spacing the same apart, said transverse frames having hangers for the bearings of a power shaft and laterally extending bracket arms carrying at their outer ends skirt guards. 35
